UNITED STATES PATENT OFFICE

BENJAMIN B. BETTS, OF ST. LOUIS, MISSOURI.

RAIL-ANTICREEPER.

1,195,769.

Specification of Letters Patent. Patented Aug. 22, 1916.

Application filed January 5, 1916. Serial No. 70,534.

To all whom it may concern:

Be it known that I, BENJAMIN B. BETTS, a citizen of the United States, and resident of St. Louis, Missouri, have invented certain new and useful Improvements in Rail-Anticreepers, of which the following is a specification containing a full, clear, and exact description, reference being had to the accompanying drawings, forming a part hereof.

My invention relates to improvements in rail anti-creepers wherein a tie engaging element is combined integrally with opposing jaws which embrace the rail base flange and which jaws are relatively disposed to permit the anti-creepers to be tilted into position on the rail, one of which jaws is arranged to receive a wedge whose function is to properly position the rail base in said jaws, and to secure the rail base against movement laterally between the jaws and longitudinally in the direction of travel of rolling stock.

The object of my improvements is to construct a simple inexpensive and efficient device for the prevention of rail creeping which may be easily and quickly applied, and which positively clamps the rail base to secure it against movements relative to the ties.

With the above object in view my invention consists in the construction and arrangement of parts hereinafter fully, clearly and concisely described, pointed out in my claims, and illustrated by the accompanying drawings, in which—

Figure 1 shows a fragment of a rail and fragment of a tie with a device embodying my invention applied as in use; Fig. 2 is a fragmental elevation of a rail and a fragment of a tie and my device shown in section, the figure being taken on the line 2—2 of Fig. 1; Fig. 3 shows in transverse section a rail having the device of my invention applied thereto, the figure being taken on the line 3—3 of Fig. 1; Fig. 4 is a plan of the device showing one jaw partly in section; Fig. 5 is a plan of the wedge, and Fig. 6 is a sectional view on a reduced scale illustrating how the anti-creepers may be tilted into position over the base flange of the rail.

Referring by numerals to the accompanying drawings, 7 designates the base or body portion of the device, which is of substantially rectangular oblong shape and whose upper face 8 is plane and of a length greater

than the width of the base or a rail. At the one end of this base or body portion there is formed an integral jaw 9 which stands over and is vertically spaced from the plane face of the base or body portion and extending laterally from the jaw 9 is a tie engaging bracket 10. At the other end of the base or body portion there is formed a jaw 11 which like the jaw 10 extends over and is vertically spaced from the plane faces of the body 7, its vertical spacing from said body being greater than the vertical spacing of the jaw 9 from said body the terminal face 12 of the jaw 11 as shown in the drawings being substantially parallel with the plane face 8 of the body while the terminal face 13 of the jaw 9 inclines relatively to the plane face 8 of the body.

The bight 14 of the jaw 11 between the plane face 8 and the terminal face 12 is arcuate in cross section and as shown in Fig. 4 this bight of the jaw 11 is inclined relative to the minor axis of the body 7.

15 designates the body of a wedge which is adapted to be forced into the space between the jaw 11 and the face of a rail and whose body 15 is transversely tapered to conform with the tapering base of a rail, and the terminal face 12 of the jaw 11, and as clearly shown in Fig. 5 this wedge is provided with a margin 16 arcuate in cross section to conform with the bight of the jaw 11 and which margin is inclined relative to the major axis of the wedge to conform with the incline of the bight 14. Between the arcuated margin 16 of the wedge and the body thereof, there are formed the channels 17 extending lengthwise of the wedge and intersecting these channels there is formed an opening 18 whereby to provide for the securing of the wedge in place. At the one end of the wedge there is an integral stop 19 whose function is to engage the jaw and limit the movement of the wedge in one direction. For preventing the movement of the wedge in the other direction, I employ a lock 20 preferably constructed of wire having its one end inserted in the opening 18, its body occupying the uppermost channel 17 and its free end extending beyond the body of the wedge whereby it may be upset or bent against the jaw 11.

By preference the portion of the plane face 8 of the body lying adjacent the jaw 11 is of greater width than the remaining portion of the plane face of the body in order

to increase the area lying beneath that portion of the rail base flange acted upon by the wedge and for the same reason the jaw 11 and the wedge 15 are of a width greater than the width of the jaw 9.

5 By preference the device is provided with strengthening ribs 21 extending around both jaws and underneath the entire body at or adjacent each side margin thereof, and 10 by preference I provide strengthening ribs 22 and 23 between the jaw 9 and the bracket 10 and the downturned portion of the bracket 10 and its body respectively.

By reason of the length of the plane face 15 of the body of the device being greater than the width of the base flange of the rail, the device may be used on various sizes of rails and by reason of the jaw 11 having greater vertical spacing from the body 8 than the vertical spacing of the jaw 9 from said body, the device may be tilted into position over the rail as shown in Fig. 6 and then moved to a position with the jaw 9 engaging snugly the base flange of the rail and 25 the jaw 11 wholly out of contact with the base flange of the rail.

After the anti-creeper has been positioned as just described the wedge 15 is placed with one end entering beneath the jaw 11 30 and then moved lengthwise of the rail in which movement it acts by reason of its inclined margin 16, to move the entire device laterally so that the back wall of the jaw 9, engages the base flange of the rail and at the 35 same time "crowds" the wedge between the terminal face 12 of the jaw and the upwardly and inwardly inclined face of the rail base flange, its motion in this direction being limited by the stop 19.

40 When fully seated as just described the wedge is locked against retrograde movement by upsetting the end of the lock as clearly shown in Fig. 2.

It will thus be seen that the device being 45 thus securely locked to the base of the rail with its bracket 10 in engagement with a tie, that creeping of the rail, incident to the movement of rolling stock thereover, is wholly obviated.

50 By reason of the arcuated inner face of the jaw 11 and the corresponding arcuated margin 16 of the wedge the device will operate with equal efficiency on rails of different dimensions by the employment of different sizes of wedges, the arcuated faces 55 permitting a slight rocking action of the wedge during insertion as well as offering a relatively small area of contact between the wedge and the jaw when seated.

60 Assuming the wedge to be in position as shown, and described, and exerting great compression upon the rail base flange, and with the entire anti-creeper at approximately right angles to the rail, it is obvious 65 that by reason of the inclined surface of the

70 rail base flange, all tendencies of the rail to move or creep as by the action of rolling stock thereover will, by reason of the anti-creeper engaging with a tie or other stationary object on the road bed, be wholly obviated for the reason that such a tendency to the creeping of the rail is directed toward a moving of the anti-creeper out of its right angular relationship with the rail and the wedge, and directed toward a climbing of 75 the inclined face of the rail base flange, hence the greater inclination of the creeper relative to the rail base, produces a proportionately greater compression or clamping action between the jaw, wedge, body of the 80 anti-creeper, and the rail base flange.

Having thus described my invention, what I claim as new therein and desire to secure by Letters Patent of the United States therefor is;

85 1. A rail anti-creeper comprising a body portion, an integral jaw at each end of the body portion, one of which jaws is designed to snugly fit one rail base flange, and the other jaw enlarged to be wholly out of contact with the opposite rail base flange, its free end overlapping the said rail base flange, a wedge for positioning between the free end of said last mentioned jaw and the inclined upper face of the rail base flange, 90 its margin engageable in the bight of said jaw, and its body wholly out of engagement with the remainder of the bight of said jaw and body of the anti-creeper, and means carried by said anti-creeper for engagement 95 with a fixed object on the road bed whereby any alteration in the angular relationship between said anti-creeper and the rail will tend to cause said wedge to ride upwardly over the inclined face of the rail base flange 100 and thus produce a greater compression or clamping action to prevent the rail from 105 creeping.

110 2. A rail anti-creeper comprising a body portion, an integral jaw at each end of the body portion, one of which jaws is designed to snugly fit one rail base flange, and the other jaw enlarged to be wholly out of contact with the opposite rail base flange, its free end overlapping the said rail base flange, a wedge for positioning between the free end of said last mentioned jaw and the inclined upper face of the rail base flange, 115 its margin engageable in the bight of said jaw, and its body wholly out of engagement 120 with the remainder of the bight of said jaw and body of the anti-creeper, means carried by said anti-creeper for engagement with a fixed object on the road bed whereby any alteration in the angular relationship between said anti-creeper and the rail will tend to cause said wedge to ride upwardly over the inclined face of the rail base flange 125 and thus produce a greater compression or clamping action to prevent the rail from 130

creeping, and means for preventing a relative movement between said wedge and the body of the anti-creeper.

3. A device of the class described comprising a body portion, a tie engaging element carried by said body, a jaw at one end of said body arranged to snugly fit the flange of a rail base a second jaw at the other end of said body arranged in opposition to said first mentioned jaw, said second jaw being larger than the first mentioned jaw to be wholly out of engagement with a rail base flange and its bight non-parallel with the bight of the first mentioned jaw, and a wedge 15 arranged to be rested upon a rail base flange and engage said second jaw only at its bight, and its uppermost portion whereby when in position on a rail, the jaw and said wedge will clamp the rail by a vertical compression between the body portion and the uppermost portion of said jaw.

4. A rail anti-creeper comprising opposing jaws one of which is arranged to snugly fit the base flange of a rail, the other of 25 which is arranged to loosely fit the opposite base flange of a rail, the bights of said jaws being relatively non-parallel, an element tapering both transversely and longitudinally, arranged to be inserted between said 30 last mentioned jaw and the base flange of a rail whereby when said element is positioned the rail will be forced laterally to cause the opposite jaw to snugly fit the rail base and the jaw co-acting with the wedge 35 exert a clamping pressure upon the rail base.

5. A device of the class described, comprising opposite jaws and a tie engaging element, the one jaw adapted to snugly fit 40 one base flange of a rail, the other jaw adapted to loosely fit the opposite base flange of a rail, the inner face of the last mentioned jaw being transversely arcuated and out of parallel with the minor axis of the device, and 45 a wedging element whose one margin is arcuated to conform with the inner margin of said last mentioned jaw.

6. In a rail anti-creeper, the combination with a rail having tapering rail base flanges, of an anti-creeper, comprising connected 50 jaws for embracing the rail base flange, an element for engagement with a fixed object on a road bed, a wedge between the upper portion of one of said jaws and resting wholly on the upper face of the tapered rail 55 base flange whereby when upon a creeping of the rail the anti-creeper in its entirety will be moved to change its angular relationship with the rail, and the gripping or clamping action increased by reason of the 60 wedge climbing the tapered rail base flange, and means for locking the wedge against movement relative to the body of the anti-creeper.

7. A device of the class described comprising a body portion arranged to underlie the base of a rail, means arising from said body for engagement with the edge of the rail base flange and means connected with said body portion for engagement with a 65 fixed object in a road bed, a jaw carried by said body at its end opposite the said element for engagement with a fixed object in the road bed, a wedge engaging the bight of said jaw, the underneath face of said jaw 70 and the upper inclined face of the rail base flange, said wedge and said jaw having no bearing on the edge of the rail base flange whereby when the wedge is seated and the device as a whole is shifted from its angular 75 position relative to the rail as by creeping created by rolling stock, said wedge will be forced upwardly over the inclined face of the rail and thus create added compression between the wedge and the jaw to more 80 firmly grip the rail.

In testimony whereof, I have signed my name to this specification, in presence of two subscribing witnesses.
